UNITED STATES PATENT OFFICE

2,518,637

PERFUME DISPENSER

John L. Priess, Chicago, Ill.

Application December 4, 1946, Serial No. 714,036

1 Claim. (Cl. 222—182)

1

My invention relates to a leak proof perfume dispenser.

Among the objects of my invention is to provide a dispenser that will not leak; that has an improved seal and an easily operated valve construction; that is easily refilled; that will not clog or become inoperative; that has a dome shaped closure for reinsurance against evaporation.

My invention also contemplates such other objects, advantages, and capabilities as will later more fully appear and which are inherently possessed by my invention.

While I have shown in the accompanying drawings, a preferred form of my invention, yet I wish it understood that the same is susceptible of modification and change without departing from the spirit of my invention.

Referring to the drawings, Fig. 1 is a longitudinal sectional view of my device; Fig. 2 is a top plan view; Fig. 3 is a disassembled view of the aligned parts and Fig. 4 is a reduced perspective view of my device in use.

The embodiment selected to illustrate my invention comprises a container 10, having a hollow interior 11 and an open top 12. A collar 13 has a lower body portion 14 extending within the hollow interior 11 and attached to container 10 adjacent the open top 12, with flange 15 resting on said top 12. Said collar has an upper portion 16 extending above said top 12 with interior screw threads 17 and exterior screw threads 18.

A valve housing 19 has a vertical bore 20 therethrough, a knurled top portion 21, and integral therewith a body portion 22 with screw threads 23 and a reduced lower portion 24.

Valve housing 19 is adapted to extend through collar 13 with its screw threads 23 engaging interior screw threads 17 of collar 13.

A valve plunger 25 has a stem 26 with a valve head 27 and a reduced shank 28 therebelow, receiving a coiled spring 29. The valve plunger 25 and spring 29 are positioned within opening 20 of valve housing 19 with stem 26 extending therabove, the upper end of stem 26 being attached to cap 30. The lower end of valve housing 19 is crimped inwardly to hold spring 29 from falling out after it has been inserted into position.

In operation when cap 30 is pressed downwardly, valve head 27 which normally is held by spring 29 against the walls surrounding a narrow portion of bore 20 for a seal, is moved downwardly into a slightly larger portion of bore 20 so that an opening is provided for the passage therebeyond of fluid in container 10.

A dome shaped closure 31 having screw threads 32 engages exterior threads 18 of collar 13 for closing the container.

2

Having thus described my invention, I claim:

A perfume dispenser comprising a cylindrical container with a hollow interior adapted to hold perfume, and an open top, a collar attached to said container within its hollow interior and having an extension extending beyond the open top of the container, the diameter of said collar being smaller than the diameter of said container, said collar having interior screw threads and on its extension outer screw threads, a valve housing having a vertical bore with an enlarged lower portion, said valve housing having a top, a screw threaded body portion and a reduced lower portion, a valve plunger having a stem, a wedge shaped head, and a reduced shank, a coil spring mounted on said shank, said valve plunger and said spring positioned within said valve housing, with the stem extending above the top of the housing, a cap attached to the top of the stem of said plunger and slidably mounted in the bore of the valve housing, said valve housing removably attached to said collar, with the screw threaded body portion of said valve housing engaging the inner screw threads of said collar and the top of the valve housing engaging the top of the extension of the collar, so that the body portion and reduced lower portion of said valve housing are positioned within the perfume dispenser, and the top portion of said valve housing and the cap and upper portion of the stem are the only parts of the valve plunger and valve housing exposed above the top of the extension of the collar, said valve head normally held by said spring against the walls of said valve housing, said stem smaller than and slidably within said bore and adapted upon downward manual pressure on said cap to move said valve head to said enlarged portion of said bore and away from said walls thereby providing an opening to permit perfume from said container to pass through said bore to be dispensed, and a screw threaded dome shaped closure adapted to removably engage the outer screw threads of said collar.

JOHN L. PRIESS.
